UNITED STATES PATENT OFFICE.

HARRY P. C. BROWNE, OF NEW YORK, N. Y.

COUNTING-MACHINE.

1,333,061.

Specification of Letters Patent. Patented Mar. 9, 1920.

Application filed December 18, 1915. Serial No. 67,588.

To all whom it may concern:

Be it known that I, HARRY P. C. BROWNE, a citizen of the United States, residing at New York, in the county and State of New York, have invented certain new and useful Improvements in Counting-Machines; and I do hereby declare the following to be a full, clear, and exact description of the invention, such as will enable others skilled in the art to which it appertains to make and use the same.

My present invention relates to improvements in counting machines of the type in which two or more wheels, displaying numerals 1, 2, et cetera to 9 and 0 on the periphery, are mounted side by side on a common central shaft.

More particularly the objects of my invention are: to provide a device of the character named which will furnish a continuous register of a cycle of movement, such as revolutions, of mechanism to which it may be coupled, whether the said cycle be reversed in direction or not; in which the setting of the counting wheels in their several positions around the central shaft is performed by means which are independent and corrective of the train actuating the wheels; in which the wheels may be readily reset to any desired reading; and of such design that a complete instrument of small size may be constructed throughout of inexpensive, dependable parts.

To the accomplishment of these objects and such others as may appear hereinafter, my invention comprises the novel construction and combination of parts hereinafter described and pointed out in the appended claims, reference being had to the accompanying drawings.

In the drawings in which the same reference characters designate like parts throughout the several views, Figure 1 is an end view in elevation of the device, a guard G with opening 29, used to cover all the numerals except those appearing in the central line, is shown in Fig. 1, but the construction and purpose of such guard being commonly understood, the guard is elsewhere omitted. Fig. 4 is a front view in elevation of Fig. 1. Fig. 2 is a sectional view on the line $e-e$ of Fig. 4 seen in the direction of the arrow, comprising only parts which are not sufficiently disclosed by Fig. 1. Fig. 3 is an isometric view of one of the counting wheels complete with ratchet and cam. Fig. 5 is

an isometric view of one of the pawls used for actuating the counting wheels. Fig. 6 is a diagram showing the action between the parts displayed in Fig. 2. Fig. 10 is an isometric view of the central shaft on which the counting wheels are supported. Figs. 7 and 8 are respectively end and front assembly views of Fig. 10 and the bracket member in which it is supported. Fig. 9 is an isometric view of the shaft which drives the mechanism with circular cams in their position thereon.

Referring to the drawings; in Figs. 10, 7 and 8, A represents a cylindrical shaft of relatively large diameter, a and a' are cylindrical bosses centrally disposed on the ends of A, and by means of which A is supported in the bracket H. The bracket H comprises the two plane parallel wings h and h' , of like shape and connected at the rear by the cross piece h'' ; the upper right hand corner of h, Fig. 7, being broken away to display notch j in wing h' . Holes f and f' , in h and h' respectively, receive bosses a' and a respectively, when the wings of the bracket, which is preferably made of a resilient material as steel, are slightly spread apart. Holes y and y' form bearings for a shaft Y, Figs. 1 and 4. Returning to Fig. 10, 1, 2, 3, 4 and 5 are sockets of cylindrical bore, uniform size and depth, and having their axes in the same plane and parallel to each other; the plane containing the axes of the sockets, passes above the axis of shaft A for reasons which will be explained under Fig. 6. A hole g passing from end to end of shaft A and paralleling the axis thereof, forms a bearing for the driving shaft B, Fig. 9. Fig. 3 represents a complete counting wheel, of which wheels five are used in the present machine: on the periphery of the wheel appears the usual series of numerals or digits, viz; 0, 1 et cetera to 9 in order in the counter-clockwise direction and at intervals of 36 degrees. The digits may be printed for sight readily only or they may be raised types for printing. Concentric with the periphery of the wheel is an opening O, originally a circle in contour, but of which circle only the relatively small arcs as indicated by o are left after the formation of the series of ten notches 6, 7, 8 et cetera around the rim of O, at intervals of 36 degrees. The arcs o are parts however of a true circle and form a bearing surface by which the counting wheels ride

upon the shaft A with any desired fit. The notches 6, 7, 8 et cetera are of circular arc contour, adapted to seat a ball V, Fig. 2, one of which balls under outward pressure 5 of a spring u confined within the socket, is carried by each of the sockets 1, 2, 3, 4 and 5. Referring again to Fig. 3, r₃ is a ratchet having ten notches or teeth t at 36 degree intervals around its outer edge; the tips of 10 the teeth are slightly flattened, the working faces t' are radial in direction, the backs of the teeth are straight from the tip of one tooth to the root of the next preceding tooth. At the left of the wheel is the circular concentric cam c₂, the diameter of 15 which is slightly greater than the ratchet diameter across the flattened tips. A single notch S, corresponding in contour to the tooth notch of the ratchet and substantially opposite to one of said ratchet teeth, is formed in the cam which, otherwise, is a plain flat disk. The wheel, cam and ratchet are by preference formed integral with each other by some process such as die casting, 20 but may be made separately and assembled in any desired way. Referring to Fig. 1, it will be noted that the notch S is located on the cam in such relation to the numeral 9 that, when the bail X is retracted to the extreme left position indicated by w, the pawl 25 now inoperatively riding the rim of the cam, will be permitted by the notch S to fall into engagement with a ratchet tooth; only however when the digit 9 shows in the line of central registration 40—41 of Fig. 4.

Referring to Fig. 1, X is a bail comprising wings x and x', alike and parallel to each other and connected by the cross piece a''; member X as a whole part being pivoted on the holes y and y' of bracket H, by means of the shaft Y. The shaft Y parallels the axis of shaft A in the assembled device, and is secured to the bail X by the expansion of its ends into corresponding holes at the bottom of x and x', the expansion being facilitated by the provision of d and d'. In the wings x and x' are formed identical slots 13 and 14, Figs. 1 and 4, which inclose the eccentric cams 21 and 22 as to lateral movement, the width of the slots being substantially equal to the cam diameter, the length of the slots is slightly in excess of twice the greatest eccentricity of the cams, but may be made still more as the slots do not necessarily inclose the vertical movement of the cams. At the upper end of the bail is fixed, in a position of parallelism with shaft A, the shaft 9, upon which are strung pawls P₁, P₂, P₃, P₄ and P₅, Figs. 1 and 4. Referring now to Fig. 5, which shows the perspective of the pawl, m and m' are parallel ears, approximating round disks in form, which are joined at the bottom by the web 15; at the forward end of 15 is the lip 16, extending to the right and offset up-

ward from the plane of the web by a space 27, equal to the thickness of the web. In the ears m and m' are central holes 10 and 11, which fit the shaft 9 and serve to pivot the pawls, as shown in Figs. 1 and 4. Springs 70 12, encircling shaft 9, between each set of ears m and m', and pressing against member a'' and upon the webs cause the pawls to bear upon the rims of the cams c₁, c₂ et cetera. A loose washer 17 locates the pawls 75 midway over the ratchet and cam of adjoining counting wheels.

Referring to Fig. 9, B is a shaft to which are affixed by pins 23 and 24, the eccentric circular cams 21 and 22, which are alike, 80 and, as mounted on the shaft, opposite to each other and normal to the shaft. Shaft B journals in the hole g, Fig. 10, the space between the cams being substantially equal to the overall length of shaft A including 85 the bosses a' and a.

In Fig. 2, the arrow shows the direction of the working movement of the counting wheel; it is evident that this movement will cause the corner v' of the notch seating the 90 ball V to press upon same, also that the reverse movement will cause the corner v'' to press upon the ball. Now referring to Fig. 6, in which Q is a circle corresponding to the circumference of shaft A, V a circle 95 corresponding to ball V, and 3 a rectangular space of oblique angle to Q and confining the movement of V; a force traveling on Q and contacting with V will tend to exert itself on a line joining the point of 100 contact with the center v of the circle V. If the point of contact be v', the force will take the direction p—v'—v, at an angle of approximately 45 degrees to the sides of the rectangle 3; if the point of contact be v'', the 105 force will take the direction b—v, substantially normal to the sides of the rectangle. In the first instance the circle V will be acted on by a component substantially equal to the original tangential force and of inward direction; in the second instance the 110 component acting on V will be negligible in amount and outward in direction. The proportions of the diagram figures are those used in the device as shown in the 115 drawings, so comparing Fig. 2 with Fig. 6, it is evident that the counting wheel may be moved in the working or clockwise direction, but that if the reverse movement be attempted the ball V will remain firmly in 120 the notch and act as a detent preventing any actual movement. This function of the ball, viz; that of acting as a detent for the counting wheels against the retractive action of 125 the pawls, constitutes an important part of my invention, as it obviates the occasion for a second series of pawls which would otherwise be needed as detents, but which would be difficult to apply effectively in a counting machine of small size.

As the corner v'' passes above the horizontal diameter of the ball V , the force of the spring u assists the movement of the wheel with increasing effectiveness as v'' rises higher, until it takes command and throws the ball into the approaching notch ahead of the action of the prime actuating means. By this action of the ball, the setting of the counting wheels in their several angular positions, is made, independent and corrective of any variations in the length of stroke of the pawls.

In Fig. 1, the bracket H is attached to a plate 20 by rivets 18, fitting the holes 28, Fig. 8; the plate 20 and the spindle 19, are similar in appearance and function to the plate Q and the spindle Q' shown in the drawings of my Patent No. 942,883 granted December 14th, 1909 and entitled Hub odometers, to which art, among others, my present invention is adapted.

The operation of the counter is as follows:—The revolution of the shaft B , with its cams 21 and 22 engaging the slots 13 and 14, causes the bail X to describe an angular movement about the axis of shaft Y . A line $z-z'$, joining the center of the shaft Y with the center of the pawl shaft 9 , passes through w of the arc $w-w'$ when the bail attains the left hand limit, Fig. 1, of this angular movement; and through w' when at the right hand limit. The position of rest of the counting wheels, determined by balls V , is such that in the position w , the pawls are retracted far enough to allow them to fall into the ratchet tooth notches; and the movement of the bail from position w to w' , provides traverse of the pawls needed to rotate the wheels through the angle of one tooth or digit interval. The notch j in h' , allows the pawl P_5 to follow ratchet r_5 to the end of the stroke. The provision of duplicate eccentric cams, engaging duplicate slots in the bail, propels the bail at each end thereof, which results in smoother and more uniform motion of the pawls than would be obtained with but one cam.

The action of the counting mechanism proper is as follows:—Pawl P_5 remains in continuous engagement with the ratchet r_5 of the units counting wheel, so that for each complete stroke of the bail, the unit counting wheel registers the net succeeding digit. Pawl P_4 , however, rides on the cam c_4 , carried by the units wheel and therefore remains inoperative until the notch in c_4 occurs in the position shown in Fig. 1, in other words, remains inoperative until the digit nine of the units wheel has assumed its place in the register sight, line 40—41 Fig. 4. When P_4 is allowed to drop, it engages the ratchet r_4 attached to the tens wheel, and will traverse the latter through one tooth or digit interval upon the next forward bail

stroke to w' , the units wheel meanwhile passing to digit 0. Thus the register will pass from 9 to 10, from 19 to 20, et cetera up to 89 when the next succeeding w' position will register 90. This position of the tens wheel, presents the notch of cam c_3 to pawl P_3 , but if P_3 were allowed to drop at this point into engagement with ratchet r_3 , attached to the hundreds wheel, the register would move to 191 with the next w' position of the bail. The lip 16 of P_3 , however, prevents the action alluded to in the following way. At registration 90, P_4 cannot drop, the notch in c_4 having been carried forward with the digit nine of the units wheel, but remains in the inoperative or elevated position, and while it so remains sustains P_3 also in the inoperative position through the lip 16, which overlies P_4 , as shown in Fig. 4. When the units wheel again registers nine, P_4 will drop and engage r_4 , at the same time allowing P_3 to drop and engage r_3 , ratchet of the hundreds wheel. The lips 16 of the pawls to the left, overlie the pawls to the right, hence the 90 pawls to the left are supported by those to the right, so that P_2 engaging the thousands wheel, ratchet r_2 , must remain inoperative until the units, tens and hundreds wheels all have assumed the position which presents 95 their respective digits 9, in the line 40—41. Likewise P_1 engaging the ten thousands wheel ratchet r_1 , must remain inoperative until the registration 9999 has appeared. Thus a continuous registration progressing 100 by units is secured up to 99999, after which the register returns to 00000, and begins again to register upward.

Referring again to Fig. 6, it is to be noted that the degree of obliquity of space 3 to circle Q determines the direction and amount of the motive effect of the forces $p-v'-v$ and $b-v$ exerted by the points v' and v'' respectively, upon circle V . Thus, if space 3 be made normal with respect to Q , 105 the angles made by $p-v'-v$ and $b-v$ with the sides of 3, will be equal; and in consequence, forces exerted by points v' and v'' alike in effect upon circle V . Also, as 3 recedes from the normal, the forces become 110 unlike; that which is approached having less and less effect upon circle V , and greater and greater effect in resisting rotation between the counting wheel and shaft A . In an arrangement of 3 normal to Q , 115 the counter wheels and shaft A would be rotatable with respect to one another with equal facility in either direction; in the arrangement shown in the drawing the wheels and shaft have but a single direction 120 each, of rotation with respect to one another. Between these extreme positions, however, the action of the balls to position the wheels undergoes no change. In the drawings, the arrangement, $b-v$ normal to 125

130

the sides of 3, is used primarily to make room for the operating shaft B, but other relationship between 3 and Q might be advantageously used in several variations of 5 the present mechanism. Still other modifications might be made in the herein described apparatus which could be used without departing from the spirit of my invention.

Having thus described my invention, what 10 I claim and desire to secure by Letters Patent of the United States, is:

1. In a counting machine, the combination of a cylindrical supporting member, of a counting wheel having a central bearing 15 and rotatably mounted on said member, the inner wall of the bearing of said wheel being provided with arcuate notches spaced a uniform distance apart, therearound, a mechanism operatively connected with said 20 wheel, and imparting successive partial rotations thereto, and means contained within said member, and interposing a yielding resistance to the rotation of said wheel upon said member in one direction, when actuated by said mechanism, said means seating in 25 said notches successively and locking said wheel against rotation relative to said member in the opposite direction.

2. In a counting machine, the combination 30 of a supporting member, an indicating wheel, having a bearing and rotatable upon said member, the bearing wall of said wheel being provided with a plurality of notches, spaced a uniform distance apart around the

wheel and forming projections between said 35 notches having sloping sides, a mechanism for rotating the wheel in one direction, a yieldably mounted means contained within said member, and seating in said notches successively as the wheel is rotated, said 40 means locking the wheel against rotation relative to said member in the opposite direction, said means operating against the rear side of each projection after it has passed the line of movement of said means, 45 to accelerate the wheel movement independent of said mechanism.

3. In a counting machine, the combination of a supporting member, having an internal socket, an indicating wheel having a 50 bearing, and rotatable upon said member, the bearing wall of said wheel being provided with a plurality of notches spaced a uniform distance apart around the wheel and forming projections between said 55 notches, a yieldable member within said socket, a ball mounted on said member and normally seated in one of said notches, said ball being disposed to permit the rotation of said indicating wheel in one direction and to 60 lock it against rotation in the opposite direction.

In testimony whereof I affix my signature in presence of two witnesses.

HARRY P. C. BROWNE.
